UNITED STATES PATENT OFFICE

159,390

CLOTHESPIN

Ancelmo J. Pineda, San Antonio, Tex.

Application July 15, 1949, Serial No. 3,942

Term of patent 7 years

(Cl. D17—6)

To all whom it may concern:

Be it known that I, Ancelmo J. Pineda, a citizen of the United States, residing at San Antonio, in the county of Bexar and State of Texas, have invented a new, original, and ornamental Design for a Clothespin, of which the following is a specification, reference being had to the accompanying drawings, forming part thereof.

In the drawings:

Figure 1 is a front elevational view of a clothespin showing my new design,

Figure 2 is a side elevational view, and

Figure 3 is a top plan view.

I claim:

The ornamental design for a clothespin, as shown.

ANCELMO J. PINEDA.
